US0D1088552S

(12) **United States Design Patent** (10) **Patent No.:** **US D1,088,552 S**
(45) **Date of Patent:** **** Aug. 19, 2025**

(54) **BAG**

(71) Applicant: **NIKE, Inc.**, Beaverton, OR (US)

(72) Inventor: **Brent Radewald**, Beaverton, OR (US)

(73) Assignee: **NIKE, Inc.**, Beaverton, OR (US)

(**) Term: **15 Years**

(21) Appl. No.: **29/886,054**

(22) Filed: **Mar. 3, 2023**

(51) **LOC (15) Cl.** **03-01**

(52) **U.S. Cl.**

USPC **D3/321; D3/216; D3/217; D29/101.3**

CLAIM

The ornamental design for a bag as shown and described.

DESCRIPTION

FIG. 1 is a right side view of a bag showing my new design;

FIG. 2 is a rear-right side perspective view thereof;

FIG. 3 is a rear view thereof;

FIG. 4 is a rear-left side perspective view thereof; and,

FIG. 5 is a left side view thereof.

The broken line immediately adjacent to the shaded area defines the bounds of the claimed design and forms no part thereof. The broken lines depicting the remainder of the bag form no part of the claimed design.

1 Claim, 5 Drawing Sheets
